[57] CLAIM

The ornamental design for a port cap for medical apparatus, substantially as shown and described.

DESCRIPTION

FIG. 1 is a side elevation of a port cap for medical apparatus embodying my new design;

FIG. 2 is a plan view of the port cap of FIG. 1 and in which certain portions are shown in section;

FIG. 3 is a right side plan view thereof;

FIG. 4 is a left side view thereof; and

FIG. 5 is a perspective view thereof.

FIG. 2.

FIG. 1.

FIG. 2.

FIG. 4.

FIG. 5.
